UNITED STATES PATENT OFFICE.

CHARLES W. HARROLD, OF CLEVELAND, OHIO, ASSIGNOR, BY MESNE ASSIGNMENTS, TO HARRIS-SEYBOLD-POTTER COMPANY, OF CLEVELAND, OHIO, A CORPORATION OF DELAWARE.

DELIVERY FOR PRINTING PRESSES.

Application filed December 29, 1926. Serial No. 157,662.

My invention relates particularly to an improved delivery for a web printing-press and more especially to web rotary presses for lithographic printing by offset impression.

- 5 The objects of my invention are, among other things, to provide an improved delivery for a rotary press of this type for printing upon both sides of the web of paper or other impression-receiving material operable in 10 combination with any suitable form of delivery mechanisms for taking the perfected web including sheet-cutting devices and a folder whereby when the impression is thrown off the press, the forward travel of the web 15 may be simultaneously slowed down to a marked extent through the press and delivery to enable the printing and offset cylinders to be run to get up color while the sheet-cutting and folding mechanisms may also continue in 20 operation, but without actually stopping the forwarding of the web through the press and without printing on such web which is caused to travel slowly through the press and delivery while the web-cutters and folder 25 continue in operation. A further object is to provide for moving and arranging the different parts of the web delivery in connection with the slowing down of the forward feed of the web which is under direct control of 30 the forwarding devices so that the different functions may be performed without disarranging the press and delivery elements or interfering with the threaded web in the press. In like manner when the web-forwarding mechanism is brought back to normal speed of operation along with the restoration of impression on the press, the web-pulling devices are always held in contact with the web so that the further advancement of 35 the web through the press with the resumption of the printing and delivery of the web to the cutters is in no way hindered and the amount of waste paper in getting up color is practically negligible.
- 40 With these and other objects in view, my invention comprises the constructions and operating parts forming the press and delivery mechanisms herein shown and hereafter to be described as one embodiment of 45 my invention, such other features being fully and specifically set forth in the appended claims.

The accompanying drawings show this embodiment of my invention in connection with 50 a web offset press printing two colors on one

side and a third color on the other side of the web, the same serving to explain the invention which is not restricted, however, to any particular form or type of printing press construction.

In the drawings, Fig. 1 is a side elevation of the improved delivery when the press is in operation and the printed web is being carried through the delivery and sheet cutters at normal speed of operation;

Fig. 2 is a side elevation of the upper portion of Fig. 1 when the press is tripped and the web is being slowly forwarded through the delivery;

Fig. 3 is an end view of Fig. 2 looking toward the left;

Fig. 4 is a top plan view of Fig. 1 showing the clutch for the delivery roller disconnected in normal operation;

Figs. 5 and 6 are detail views of the rock arms for the web-forwarding devices;

Figs. 7 and 8 are detail views of the idler wheels for the web-delivery roller and their operating mechanism;

Fig. 9 is a perspective view of the supporting bracket for one end of the delivery roller;

Fig. 10 is a detailed end elevation of the disconnected clutch and the delivery roller with mechanism for operating the clutch;

Fig. 11 is a view similar to Fig. 10 showing the clutch in operative engagement with the delivery roller to rotate same at reduced speed when the press is tripped; and

Fig. 12 is a diagrammatic side elevation of a web offset press and delivery embodying the improvements in conjunction with sheet-cutters, a folder and end delivery.

Similar numerals refer to similar parts throughout the several figures.

Referring to Figs. 1-4, the side-frames 13 and 14 of the delivery have journaled therein the shafts 15 and 16 which carry the cutting cylinders 17 and 18 respectively in which are affixed the transverse coating cutting knives 19 and 20 for severing the web W into sheets. The cylinders 17 and 18 are driven in unison by the intermeshing gears 21 and 22 keyed to the shafts 15 and 16, respectively (Fig. 1). The shaft 15 is driven by the bevel gear 23 attached to this shaft which gear 23 engages the bevel gear 24 fastened to the upper end of the vertical drive shaft 25 journaled in the bracket 26 secured to the side-frame 13.

The web W is drawn forwardly in the di-

rection of the arrows or advanced through the delivery by the positively-driven forwarding or web-pulling roller 27 mounted on the shaft 28 journalled in the side-frames 13 and 14 as shown in Figs. 1 and 3. The shaft 28 carries the pinion 29 meshing with the idler gear 30 mounted on the stub-shaft 31 journalled in the side-frame 13 which gear 30 engages with the gear 21 mounted on the shaft 15 (Fig. 1). By this mechanism the forwarding roller 27 for pulling the web W forwardly is rotated in the same direction and at the same peripheral speed as that of the cutting cylinders 17 and 18. Coacting with the web-forwarding roller 27 are two spaced-apart drop rollers 32 and 33 (Fig. 3), which when pressing the web W against the driven roller 27 as shown in Fig. 1 cause the web to be pulled by the roller 27 to advance same through the delivery as shown in Fig. 1.

The drop rollers 32 and 33 are pinned to the lower ends of the rock-levers 34 and 35 journalled on the rock-shaft 36 journalled in the side-frames 13 and 14 (Figs. 1, 3 and 4). Keyed to the shaft 36 on either side of the rock-levers 34 and 35 are the vertical forked brackets 37 and 38 respectively having the interiorly threaded blocks 39 and 40 at their upper ends. The upper ends 41 and 42 of the rock-levers 34 and 35 have bores cut therein through which pass the adjustable screw bolts 43 and 44 with their inner threaded ends coacting with the threaded blocks 39 and 40 respectively carried by the brackets 37 and 38. Coiled about the bolts 43 and 44 between the blocks 39 and 40 and lever ends 41 and 42 are the helical springs 45 and 46 by which the pressure of the drop rollers 32 and 33 on the web-forwarding roller 27 may be properly adjusted for different grades of paper stock by turning the knurled caps 47 and 48 affixed to the outer ends of the screw-bolts 43 and 44. The springs 45 and 46 also serve through their variably-regulated tension to control the timing of the coaction of the drop-rollers 32 and 33 with the web W and also their movement therefrom. A lost motion connection is provided between the brackets 37, 38 and the arms 41, 42 by adjusting the screw-bolts 43, 44 whereby a space is provided between the reduced portion of the knurled caps 47 and 48 and their respective arms 41, 42 (Fig. 1 showing such construction only as to the arm 41 and cap 47). The rock-shaft 36 is actuated by the rock-arm 49 keyed to the shaft 36 which arm 49 carries in its outer end the tubular housing 50 (Fig. 5). Passing through the housing 50 is the slidable pin 51 having coiled about its shank 52 the helical spring 53 one end of which bears on the shoulder 54 encircling the base 55 of the pin plug end 56, while the other end of the spring 53 bears against the bottom of the cylindrical bore

cut in the housing 50. The pin plug end 56 is adapted to engage either the upper hole 57 or lower hole 58 formed in the face-plate 59 of the rock-arm 60 journalled on the rock-shaft 36. By this mechanism the drop rollers 32 and 33 may be placed in operative position against the web W and roller 27 as shown in Fig. 1 with the upper hole 57 engaged by the plug end 56, or the drop rollers 32 and 33 may be entirely swung away, 70 and held in inoperative position with respect to the forwarding roller 27 by lowering the rock-arm 49 so that the plug end 56 shall slip into and engage the lower hole 58 so that the drop rollers 32 and 33 clear the web 80 in all positions of the rock-levers 34 and 35. The pin 51 carries the knurled cap 61 (Figs. 5 and 6) so that the pin 51 may be properly manipulated to shift the plug end 56 from either hole 57 or 58 to the other as required. 85

As shown in Figs. 1 and 2, the web W passes upwardly from the press (Fig. 12) in the direction of the arrows over the compensating roller 62 by which the tension of the web W as it passes through the delivery is regulated. This roller 62 is pinned to the end of the rock-arm 63 affixed to the shaft 64 journalled in the side-frames 13 and 14. Keyed to the shaft 64 is the rock-arm 65 having the interiorly threaded block 66 affixed to its free end. Engaging the threaded block 66 is the threaded tip 67 of the rotatable rod 68 journalled in the bracket 69 and operated by the handle 70 affixed to its lower end (Fig. 1). By this mechanism the operator may 100 suitably adjust the tension of the web W by shifting the position of the roller 62 in rotating the rod 68 through the block 66 in either direction.

When the press is tripped for any reason 105 the web-forwarding devices comprising the driven roller 27 and the drop-rollers 32 and 33 are separated and let go of the web W, and novel means are provided whereby such web travelling at normal speed shall be simultaneously slowed down under the control of a positive feed so that such web W may continue its forward travel through the press and delivery at a greatly reduced speed thereby preventing the web from backing up or 110 becoming misplaced in such delivery and press. In the present embodiment best shown in Figs. 1-4 and 9-11, the side-frames 13 and 14 carry the upright bearings 71 and 72 respectively in which is journalled the cross-shaft 73 on which the idler delivery roller 74 is sleeved so as to rotate freely on the shaft 73. The shaft 73 carries the bevel gear 75 meshing with the bevel gear 76 mounted on the short shaft 77 journalled in the 115 sleeve bracket 78 affixed to the side-frame 14 (Fig. 3). Keyed to the lower end of the shaft 77 is the gear 79 engaging with the worm 80 secured to the end of the shaft 28 projecting through the side-frame 14. 120

this mechanism the shaft 73 is slowly revolved at all times in the normal operation of the delivery from the positively-driven shaft 28 while the press is in operation.

5 The delivery roller 74 is held in proper position transversly on the shaft 73 between the side-frames 13 and 14 (Fig. 4) by the bracket 81 (Fig. 9) bolted to the side-frame 13 which bracket 81 carries the forked end 82 10 which engages and rides in the annular groove 83 cut near the end of the roller 74 as shown in Figs. 4 and 9. The web W passes over the delivery roller 74 before travelling downwardly through the web-forwarding devices 15 hereinbefore described, the roller 74 being free to revolve with the same speed as that of the web W in its forward travel through the press and delivery.

Coacting with idler delivery roller 74 are 20 two spaced-apart idler wheels 84 and 85 pivoted to the inner ends of the rock-levers 86 and 87 rotatably mounted on the rock-shaft 88 which is journaled in the extension brackets 89 and 90 of the side frames 13 and 14 25 respectively. Keyed to the shaft 88 on either side of the rock-levers 86 and 87 are the horizontally extending forked brackets 91 and 92 respectively having the interiorly threaded blocks 93 and 94 on their outer ends. The 30 upper ends 95 and 96 of the rock-levers 86 and 87 have vertical bores cut therein through which pass the adjustable screw-bolts 97 and 98, with their threaded ends coacting with the threaded blocks 93 and 94 respectively 35 of the brackets 91 and 92 (Figs. 1 and 3). Coiled about the bolts 97 and 98 between the blocks 93 and 94 and lever ends 95 and 96 are the helical springs 99 and 100 by which the pressure of the wheels 84 and 85 on the 40 delivery roller 74 and also the timing of the movement of the wheels 84 and 85 against the web W, in conjunction with the lost motion connection hereinbefore described, may be suitably regulated by turning the 45 knurled caps 101 and 102 affixed to the tops of the screw-bolts 97 and 98. The rock-shaft 88 is actuated by the rock-arm 103 keyed to such shaft and the outer end of the rock-arm 103 carries the tubular housing 104 (Fig. 5). Passing through the cylindrical bore of the housing 104 is the slideable pin 105 having coiled about its shank 106 within the housing bore the helical spring 107 one end of which bears on the shoulder 50 108 encircling the base 109 of the plug end 110, while the other end of spring 107 bears against the bottom of the housing bore (Fig. 5). The pin plug end 110 is adapted to engage either the upper hole 111 or lower hole 55 112 cut in the face plate 113 of the rock-arm 114 journaled on the rock-shaft 88. By this mechanism the wheels 84 and 85 may be placed in operative position with the delivery roller 74 (Figs. 2 and 3) when the lower 60 hole 112 is engaged by the plug end 110, or

the wheels 84 and 85 may be shifted and lifted to inoperative position even when the press is tripped (Fig. 2), by having the plug end 110 engage the upper hole 111. The pin 105 carries the knurled cap 115 (Figs. 2 and 5) by which the pin 105 may be properly manipulated to shift the plug end 110 from either hole 111 or 112 to meet the requirements of proper operation. The inter-adjustment of the two sets of springs 45, 46 70 and 99, 100 control the relative movements of the drop rollers 32, 33 and the wheels 84, 85 to and from their respective engagements with the web W in conjunction with the lost motion connection shown in Figs. 1, 2 and 3. 80

To positively drive the idler delivery roller 74 with the shaft 73 when the press is tripped so that the web W may continue to be forwarded slowly through the delivery, I have devised the following mechanism best shown 85 in Figs. 3, 4, 10 and 11: Slidably keyed to the shaft 73 near the side frame 14 is the clutch member 116 having the inwardly projecting lug 117 adapted to engage with the recess 118 (Fig. 10) cut in the end of the delivery roller 90 74 as shown in Fig. 11, at which times the roller 74 is driven in unison with the shaft 73 which, in turn, is driven from the shaft 28 as has been heretofore described. When the clutch 116 is disconnected with the roller 74 95 (Figs. 4 and 10), the roller 74 freely revolves on the shaft 73 at the same speed as that of the web W. Secured to the side-frames 14 is the bracket 119 on which is pinned the bell-crank lever 120 carrying the roller 121 which 100 engages and rides in the annular groove 122 cut in the clutch member 116 (Figs. 4 and 10). The arm 123 of the lever 120 is connected by the link 124 to the rock-arm 125 keyed to the rock-shaft 88 as shown in Figs. 105 3 and 4. When the wheels 84 and 85 are lowered into contact with the web W to press same against the delivery roller 74 when the press is tripped (Fig. 2), the link 124 is also lowered to slide the clutch 116 to the left 110 (Figs. 3 and 11) into operative engagement with the roller 74 which is then positively driven from the shaft 73. For example, the speed of the web W in normal operation (Fig. 1) may be at the rate of 100 feet per 115 minute, while the speed of the web when driven from the roller 74 when positively actuated by the shaft 73 in conjunction with the wheels 84 and 85 may be as low as 4 feet per minute. Any other suitable ratio may 120 be used so long as the web W is slowly advanced by the roller 74 when positively driven from the shafts 28 and 73.

The tips of the rock-arms 60 and 114 are connected by the link 126, and the rod 127 125 pinned to the rock-arm 60 is connected with the throw-off mechanism of the press shown in Fig. 12.

Referring to Fig. 12 the web offset press therein shown in more or less diagrammatic 130

form comprises three printing couples A, B and C of which couples A and B are adapted to print on one side of the web W, while couple C prints a single color on the opposite side so as to perfect the web. The particular form and arrangement of the printing couples and their connecting throw-off mechanisms for tripping the press are not important and in themselves do not constitute my invention. In Fig. 12 couples A and B are built as a five-cylinder unit with form-cylinders D and E, transfer cylinders F and G and a common impression cylinder H, all of which are of equal diameter and are geared together to rotate in unison. Power is supplied to the press from the line shaft 128 carrying the bevel gear 129 meshing with the intermediate gear 130 connected with the gearing on the impression cylinder H. The printing couple C comprises the form cylinder I, transfer cylinder J and impression cylinder K, all of like diameter and geared together to rotate in unison by power derived through intermediate gear 131 connected with the impression cylinder K and bevel gear 132 affixed to the line shaft 128. The form cylinders D, E and I have suitable inking and water dampening mechanisms as shown, while the transfer cylinders F, G and J and the impression cylinders H and K are all mounted in eccentric bearings provided with the usual throw-off and throw-on mechanisms to trip the press as well as to restore impression in the customary manner by the operation of the trip-lever 133 adjacent the transfer cylinder G. The trip-lever 133 is connected by link 134 to line shaft 135 and the trip mechanism for printing couple C is connected by link 136 to line 135. The rocking of line shaft 135 when the press is tripped simultaneously lowers the rod 127 connected with my improved delivery as hereinbefore described. The web W (shown by dash and dot line) is fed to the press from the usual paper roll R around the impression cylinder H and thence is led to printing couple C whereby the web W is perfected with two colors on one side and one color on the reverse side. The printed web W is then passed over suitable idler rollers until it appears on the left side of Fig. 1 to be advanced through my improved web-slow-down and web-forwarding devices hereinbefore described operating in conjunction with the cutting cylinders 17 and 18. After the printed web W has been severed into sheets the latter are carried to the collecting cylinder L and then to the folder M which deposits the folded sheets on the flat end delivery N in the usual way. The operation of my improved delivery in connection with the web offset press shown in Fig. 12 is substantially as follows: Fig. 1 illustrates the position of the various parts when the press is in operation and the web W is running freely over the idler delivery

roller 74 with the wheels 84 and 85 raised to inoperative position, the web being pulled forwardly by the drop rollers 32 and 33 pressing the web W against the forwarding roller 27. Such web W then drops down into the bite of the cutting cylinders 17 and 18 which severs same into sheets that are then carried to the collecting cylinder L, folder M, and end delivery N as hereinbefore described. When the press is tripped the connecting rod 127 is lowered and pulls down the rock-arms 60 and 114 which are connected by the link 126. This movement throws the drop rollers 32 and 33 out of contact with the forwarding roller 27 and at the same time brings the wheels 84 and 85 down into contact with the idler delivery roller 74 as shown in Figs. 2 and 3, and simultaneously the link 124 is also depressed to throw the clutch member 116 to the left into engagement with the recess 118 (Figs. 3 and 11) of the delivery roller 74 to cause same to revolve slowly in conjunction with the shaft 73. As shown in Figs. 2 and 3 the web W is held by the wheels 84 and 85 pressing same against the roller 74 which is slowly revolved in a clockwise direction to advance the web through the press and delivery. This mechanism is timed by the hereinbefore described lost motion connection and by the inter-adjustment of the springs 45, 46 and 99, 100 through adjustment of the screw bolts 43, 44 and 97, 98, so that such wheels 84 and 85 come into contact with the web W and roller 74 as soon as the drop rollers 32 and 33 actually let go. By such means it will be seen that any tearing or crumpling of the web in the delivery is prevented nor does the web W ever back up or become misplaced with respect to the cutting cylinders 17 and 18 or the other sheet-manipulating mechanisms which continue in normal operation while the press is tripped. The slow feed of the web renders the amount of waste paper negligible. When the impression is restored through the press by the raising of the rod 127, the engagement of the wheels 84 and 85 with the delivery roller 74 ceases and the clutch 116 is released so that the roller 74 is free to revolve again on the shaft 73 as in normal operation with the forward pulling of the web W through the press and delivery because the drop rollers 32 and 33 are likewise brought back into web-feeding position (Fig. 1).

While the foregoing sets forth one embodiment of my invention, many changes in the structural details may be made without departing from the principles and scope of the invention or sacrificing the chief advantages involved.

I claim as my invention:

1. In a delivery for web printing-presses, means for advancing the web through the press and delivery, means for rendering said web-advancing means ineffective, and sepa-

- rate means for advancing the web at a different speed when said first web-advancing means becomes ineffective.
2. In a delivery for web printing-presses, means for advancing the web through the press and delivery at the speed of the press, means for rendering said web-advancing means ineffective, and separate means for advancing said web at a relatively slower speed when said first web-advancing means becomes ineffective.
3. In a delivery for web printing-presses, a trip mechanism for the press, means for advancing the web through the press and delivery, means for rendering said web-advancing means ineffective, and separate means controlled by said press trip mechanism for advancing the web when said first web-advancing means becomes ineffective.
4. In a delivery for web printing-presses, a trip mechanism for the press, means for advancing the web through the press and delivery at the speed of the press, means for rendering said web-advancing means ineffective, and separate means controlled by said press trip mechanism for advancing said web at a relatively slower speed when said first web-advancing means becomes ineffective.
5. In a delivery for web printing-presses, means for advancing the web through the press and delivery and separate means for imparting a relatively slower forward movement to the web when said first means becomes inoperative.
6. In a delivery for web printing-presses, means for advancing the web through the press and delivery at the speed of the press and separate means for imparting a relatively slower movement to the web when said first means becomes inoperative.
7. In a delivery for web printing-presses, a trip mechanism for the press, means for advancing the web through the press and delivery, and separate means for imparting a relatively slower forward movement to the web through the delivery when said first means becomes inoperative, both said means being controlled by said trip mechanism.
8. In a delivery for web printing-presses, a trip mechanism for the press, means for advancing the web through the press and delivery, and means for imparting a relatively slower movement to the web through the delivery when said first means becomes inoperative, both said means being simultaneously controlled and actuated by said trip mechanism.
9. In a delivery for web printing-presses, a trip mechanism for the press, means for advancing the web through the press and delivery at the speed of the press, and separate means for imparting a relatively slower forward movement to the web through the delivery when said first means becomes inoperative, both said means being inter-
- changeably controlled and actuated by said trip mechanism.
10. In a delivery for web printing-presses, a trip mechanism for the press, means for advancing the web through the press and delivery at the speed of the press, means for throwing off said means controlled by said trip mechanism, means for rendering said web-advancing means ineffective, and separate means brought into action by said trip mechanism in tripping the press for imparting a relatively slower forward movement of the web whenever said first web-advancing means is thrown out of action.
11. In a delivery for web printing-presses, a trip mechanism for the press, means for advancing the web through the press and delivery at the speed of the press, means for cutting the web into sheets beyond said web-advancing means, separate means for imparting a relatively slower forward movement to the web through the delivery when said first means becomes inoperative, and operative connections between said trip mechanism and both the web-advancing means to interchangeably control the action of the latter.
12. In a delivery for web printing-presses, means for advancing the web through the press and delivery, separate means for imparting a relatively slower forward movement to the web when said first means becomes inoperative, and means for placing either of said last-mentioned means in inoperative position.
13. In a delivery for web printing-presses, means for advancing the web through the press and delivery at the speed of the press, and separate means for imparting a relatively slower forward movement to the web when said first means becomes inoperative, and separate means for placing each of said last-mentioned means in inoperative position.
14. In a delivery for web printing-presses, a trip mechanism for the press, means for advancing the web through the press and delivery at the speed of the press, means for imparting a relatively slower forward movement to the web when the press is tripped, both said means being controlled by said trip mechanism, and means for placing either of said last-mentioned means in inoperative position irrespective of the action of said press trip mechanism.
15. In a delivery for web printing-presses, a trip mechanism for the press, means for advancing the web through the press and delivery at the speed of the press, means for imparting a relatively slower forward movement to the web when the press is tripped, both said means being controlled by said trip mechanism, and separate means for placing each of said last-mentioned means in inoperative position irrespective of the action of said press trip mechanism.

16. A web printing-press comprising web printing and delivery devices through which the web is threaded, means for actuating said printing and delivery devices to print and forward the web, and means permitting the actuation of said printing devices without printing and without unthreading the web while forwarding said web at a different speed through the press and delivery.
17. A web printing-press comprising web printing and delivery devices through which the web is threaded, means for actuating said printing and delivery devices to print and forward the web at the speed of the press, and means permitting the actuation of said printing devices without printing and without unthreading the web while forwarding said web at a relatively slower speed through the press and delivery.
18. A web printing-press comprising web printing devices and delivery through which the web is threaded, means for actuating said printing and delivery devices thereby printing and delivering the web, means for tripping the printing devices, and separate means for continuing the delivery of the threaded web at a different speed without printing and unthreading when said printing means is tripped.
19. In a web printing press, means for advancing the web through the press at its normal printing speed, means for throwing off the impression, and means for advancing the web at a different speed when the impression is thrown off.
20. In a web printing press having co-acting printing members, means for advancing the web through the printing members at printing speed, means for separating the printing members, and means for changing the speed of the web when the printing members are separated.
21. In a web printing press, means for advancing the web, means for throwing off the impression, and means controlled by said impression throw-off for changing the speed of the web when the impression is thrown off.

CHARLES W. HARROLD.
